UNITED STATES PATENT OFFICE

RUDOLF BLANCKERTZ, OF BERLIN, GERMANY, ASSIGNOR TO FIRM HEINTZE & BLANCKERTZ, OF BERLIN, GERMANY

ENGRAVING TOOL

Application filed December 13, 1930, Serial No. 502,213, and in Germany July 8, 1930.

This invention relates to a new form of tool, and more particularly a tool for performing chase work, engraving, etc., in metal foil.

8 Tools of the kind in question as hitherto employed consist of an engraving needle rigidly secured to the hand-manipulating portion, for example a wooden handle, and permit, by reason of their cylindrical form 10 and extremely small dimensions, the production of merely very fine lines.

The tool according to the invention comprises a semi-cylindrical shaft of hard metal, for example hardened steel, having a cranked 15 or set-off portion passing over into a flat, shield-like member, the free end of which serves for performing the engraving and may be furnished with any appropriate form. The part of semi-circular cross-section serves, 20 in the manner of a nib, for introduction into the holder which, if desired, may be an ordinary pen-holder. The free end of the flat, shield-like section may be tapered and rounded off according to different diameters, or 25 alternatively may be furnished with a wide tip, which in turn may either be straight or shaped in desired form. If the width permits thereof, the tip will preferably be provided with points. In order to impart to the 30 flat, shield-like portion the necessary stiffness required by the engraving operation, the same may be suitably embossed, for example with the name or the trademark of the manufacturer or with any other suitable wording 35 or design.

The advantages derived from the new tool in face of the known forms may be summarized in the following:

Owing to the cylindrical form of shaft 40 tools having selectively formed engraving tips may be fitted and employed as desired in the one holder. The holder may consist of a pen-holder of the usual type, which greatly facilitates the manipulation and reduces the outlay to a minimum, a feature of considerable advantage in the case of schools, etc. The different forms of tip permit of the production of different widths of line, so that 45 the engraving may be executed in fine or wide tracings as desired. As compared with tools

of the existing kind the new form of tool offers very considerable advantages as regards the cost of production, as the latter is performed by a simple stamping or pressing operation.

55 The invention will now be described more fully with reference to the accompanying drawings, in which in the different figures the same reference characters have been employed to denote like parts.

Fig. 1 shows in plan view different embodiments of the engraving tool or nib, the tips being of pointed, rounded or wide form with or without teeth or serrations.

Fig. 2 is an elevational view of any of the 65 tools or nibs according to Fig. 1.

Fig. 3 is a perspective view of the tool fitted in a holder, for example a pen-holder.

In the drawings *a* represents the part-cylindrical shaft, possessing a cranked or set-off portion *b* passing over into a flat, shield-like section *c*, the free end of which forms the engraving tip. This tip *d* may be provided with any desired form suitable for the intended purpose. The flat portion *c* may be 70 embossed as at *e* for the purpose of stiffening, for example with the name or the trademark of the manufacturer or with any other suitable wording or design. For the purpose of 75 use the tool or nib is fitted in a holder *f*.

80 The manipulation of the tool is extremely simple, and does not differ fundamentally from that of the ordinary engraving tool. The metal foil, which may be of any appropriate kind, such as tin, soft brass or copper, aluminum, etc., is placed, for example, on a flat, resilient base, which may consist of a piece of linoleum, a layer of paper, a sheet of cardboard, pasteboard or the like, and engraved either free-handed or according to a 85 desired pattern. Dependent on the pressure applied and the width of the tip used impressions of varying width or depth are obtained in the foil which appear on the rear face thereof in the form of embossed or elevated 90 portions. In this manner it is possible to produce any type of line, either in simple straight form or in circular pattern or design.

95 If desired, the foil may also be worked upon on the rear face, which has the addi- 100

tional advantage that any stresses arising from the action of the tool on merely the front face of the foil and tending to buckle the same are thus compensated.

5. Subsequent working on the rear face of the foil will cause the latter to retain its flat form.

To produce wider or larger impressions, the round end of the holder may be employed.

If lines are drawn straight across the foil, 10 the latter will readily fold and may thus be formed into boxes or other articles of desired shape. Other examples of possible utilization are badges, brooches, door fittings, name plates, box lids, metallic signs, fancy boxes, 15 hand-mirrors, etc., or, on a larger scale, ornamental work for doors or clock cases, commercial signs, tablets, etc.

It will be understood that no restriction is made to the specific forms of tool or nib shown 20

20 in the drawings, and that various modifications are quite possible within the meaning of the above and the annexed claims without departing from the spirit of the invention.

What I claim as new and desire to secure 25 by Letters Patent is:

1. As a new article of manufacture, an engraving tool comprising a part-cylindrical shaft, a flat, rigid, non-flexible, shield-like portion having an engraving tip, and a 30 cranked portion connecting the said flat portion and the said shaft, the said shaft being adapted to fit in exchangeable fashion in a holder.

2. As a new article of manufacture, an engraving tool comprising a part-cylindrical shaft, a flat, rigid, non-flexible, shield-like portion having a tapered end with pointed tip, and a cranked portion connecting the said flat portion and the said shaft, the said shaft 35 being adapted to fit in exchangeable fashion in a holder.

3. As a new article of manufacture, an engraving tool comprising a part-cylindrical shaft, a flat, rigid, non-flexible, shield-like 45 portion having a tapered end with rounded tip, and a cranked portion connecting the said flat portion and the said shaft, the said shaft being adapted to fit in exchangeable fashion in a holder.

4. As a new article of manufacture, an engraving tool comprising a part-cylindrical shaft, a flat, rigid, non-flexible, shield-like portion having a tapered end with wide straight tip, and a cranked portion connecting the said flat portion and the said shaft, the said shaft 55 being adapted to fit in exchangeable fashion in a holder.

5. As a new article of manufacture, an engraving tool comprising a part-cylindrical shaft, a flat, rigid, non-flexible, shield-like portion having a tapered end with wide shaped tip, and a cranked portion connecting the said flat portion and the said shaft, the said shaft 65 being adapted to fit in exchangeable fashion in a holder.

6. As a new article of manufacture, an engraving tool comprising a part-cylindrical shaft, a flat, rigid, non-flexible, shield-like portion having a tapered end with serrated tip, and a cranked portion connecting the 70 said flat portion and the said shaft, the said shaft being adapted to fit in exchangeable fashion in a holder.

7. As a new article of manufacture, an engraving tool comprising a part-cylindrical shaft, a flat, rigid, non-flexible, shield-like portion embossed for the purpose of stiffening and having an engraving tip, and a cranked portion connecting the said flat portion 75 and the said shaft, the said shaft being 80 adapted to fit in exchangeable fashion in a holder.

8. As a new article of manufacture, an engraving tool comprising a part-cylindrical shaft, a flat, rigid, non-flexible, shield-like portion having an engraving tip, a cranked portion connecting the said flat portion and the said shaft, and a holder having a rounded end and adapted to receive the 85 said shaft in exchangeable fashion at the 90 other end.

9. As a new article of manufacture, an engraving tool for embossing metal sheets comprising a part-cylindrical shaft, a flat rigid, non-flexible shield-like portion having an 95 engraving tip, and a cranked portion connecting the said flat portion and the said shaft, said flat portion extending longitudinally beyond said shaft and substantially in the basal plane of said part-cylindrical shaft, said shaft 100 being adapted to fit in exchangeable fashion into a holder.

In testimony whereof, I affix my signature.

RUDOLF BLANCKERTZ.
